SYNCHRONIZED SECONDARY CLOCK
MOVEMENTLucien B. Stone, South Orange, N. J., assignor to
Self Winding Clock Company, Inc., Brooklyn,
N. Y., a corporation of New York

Application August 19, 1939, Serial No. 290,990

4 Claims. (Cl. 58—34)

My invention relates to synchronized secondary clock movements which receive at stated periods, such as for instance hourly and on the hour, a synchronizing impulse from the master clock by which the clock is re-set to the correct time in case it should be fast or slow. Re-setting mechanisms for clocks per se are old in the art, and the present invention refers rather to a particular mechanism for accomplishing this effect in a simple and convenient manner. The particular advantages of my novel construction are the possibility of bringing about the synchronizing motion by only one single impulse of the synchronizing movement; further, that only one single magnet with a one-pulse movement is required to accomplish the synchronizing; further, means for preventing the synchronizing motion when the clock is on time so as to avoid unnecessary wear on the synchronizing elements, and other detail improvements which will appear from the following description.

My invention is illustrated in a number of modifications in the accompanying drawings in which

Fig. 1 is a rear elevation of my improved synchronizing secondary clock;

Fig. 2 is a horizontal section taken substantially on line 2—2 of Fig. 1 with parts left out for clearness;

Fig. 3 is an exploded perspective of parts shown in Figs. 1 and 2;

Fig. 4 is a fragmentary elevation showing parts of Figs. 1 and 2, in operated position; and

Fig. 5 is a fragmentary rear elevation of part of the clock movement shown in Figs. 1 to 4, illustrating a locking mechanism for holding the ratchet wheel locked while the synchronizing arm and parts are returning to normal position.

Referring to Figs. 1 through 4, 1 represents the front plate of the clock on which the dial (not shown) is mounted and on the rear of which the clock movement is mounted which is shown in the rear view of Fig. 1. It is assumed in this modification, as well as in the other modifications, that the secondary clock is normally operated by means of electromagnetic impulses controlled by the master clock and which may, as is the usual practice, occur at minute intervals. For this purpose, as shown in Figs. 1 and 2, the following mechanism is provided. 2 represents the clock frame in which the minute arbor 3 and the hour clock train 3a are journaled in conventional manner. On the minute arbor 3 is fixed a ratchet wheel 4 which is operated step by step at minute intervals, for instance in the following manner.

In the lower part of the clock frame 2 is mounted electromagnet 5 which is energized at these intervals from the master clock, and the armature 6 of which is fixed to a feeding lever 7 pivoted in the clock frame at 8 and limited in its outward swing by an adjustable stop 9. The lever is yieldingly pressed against this stop by means of a spring 10 bearing against the upper free end of lever 7 and seated in an adjusting screw 12 threaded into a standard 11 so that the pressure of spring 10 can be regulated. When electromagnet 5 is energized, the lever is swung clockwise, thereby tensioning spring 10, and as soon as the impulse ceases, the spring throws the lever 15 7 counterclockwise against stop 9. On the free end of feeding lever 7 is pivotally mounted feeding pawl 14 so that its left-hand end engages the teeth of ratchet wheel 4. On feeding lever 7 is provided a flat spring 16 which presses 20 against a detent 15 of feeding pawl 14, whereby the latter is normally held in engagement with the ratchet teeth. On clock frame 2 is further pivotally mounted at 20 a retaining pawl arm 18 which is illustrated in detail in Fig. 3. 25 This arm is provided with a substantially rectangular portion 36 at the lower end of which extends a detent 19 at right angles to the plane of arm 18, so that in the position in which arm 18 is mounted, pawl 19 extends across the teeth 30 of ratchet wheel 4 and prevents the latter from moving counter to the direction of the arrow in Fig. 1.

This feeding mechanism, so far described, operates in conventional manner as follows: Normally, feeding arm 7 is in the position shown in Fig. 1. As soon as an impulse is received at magnet 5, the arm is swung clockwise and thereby pawl 14 is withdrawn to the right by one tooth so that it falls into the next tooth, and as soon as the magnet is deenergized, spring 10 40 thrusts arm 7 to the left, thereby feeding wheel 4 and thus the minute arbor by one tooth counter-clockwise in Fig. 1.

In order to re-set the minute arbor in case it 45 should be fast or slow, the following mechanism is provided. In the upper portion of clock frame 2 is mounted an electromagnet 21 which cooperates with an armature 21a which is attached to a re-setting arm 22 normally held by a tension spring 26 against a stop 27 as shown in Fig. 1. This arm is pivoted in the clock frame at 23 and is ox-bow shaped at its lower end as shown at 24, so that it can straddle at that end the minute arbor 3. On ratchet wheel 4 is provided 50 55 a pin 25 in such a position that when it stands

symmetrically to the ox-bow when the latter is thrown into the dotted position, the clock hands are located in the desired set or synchronized position, for instance exactly on the hour. If during the time when arm 22 is attracted by electromagnet 21 and thrown towards the dotted position in Fig. 1, pin 25 should be to the right or to the left of the position shown in Fig. 1, the ox-bow will take the pin along and shift it into the position shown in Fig. 1 and thereby re-set the clock to the proper time.

In order to re-set the minute arbor, however, the feeding and retaining pawls 14 and 19 must be released from ratchet wheel 4 so that the latter can be freely turned by the re-setting arm. For this purpose, a release link 26 is pivotally attached at 26a to re-setting arm 22, and at its other end to a release cam 29 which is pivotally attached at 30 to the clock frame. This cam has two functions. First, in normal position as shown in Fig. 1 it prevents feeding pawl 14 from accidentally being thrown upwardly during the ordinary feeding motion of the feeding arm 7 by means of a detent 31 which is in the position shown in Fig. 1 located closely above detent 34 at the left-hand end of feeding pawl 14 without touching the latter so that no friction is encountered thereby. Thus the feeding pawl can move unhindered to the right, but cannot accidentally be thrown upwardly. The second function of release cam 29 is exercised by means of a pin 32 extending across the cam-shaped surface 33 of feeding pawl 14. Thus if during the re-setting operation re-setting arm 22 is moved into the dotted position, link 26 throws re-setting cam 29 in counter-clockwise direction and thereby first of all the detent 31 moves away from the transversely bent end 34 of pawl 14 which normally rests against the teeth of ratchet wheel 4, and secondly pin 32 moves along the cam surface 33 of feeding pawl 14, thereby throwing the latter in clockwise direction against the tension of its spring 16. This position is shown in Fig. 4. Feeding pawl 14 is arranged in a relation to the rectangular portion 36 of arm 18 such that detent 34 of pawl 14 extends through the square opening of rectangle 36 and rests normally against the upper edge thereof, as shown in Fig. 1. Thus if feeding pawl 14 is thrown clockwise by the re-setting mechanism, as shown in Fig. 4, the frame 36 is lifted into the position shown in Fig. 4, whereby the retaining pawl 19 attached to portion 36 is lifted off the ratchet tooth of wheel 4 with which it was previously in engagement. Thus both pawls are now removed from ratchet wheel 4 and the latter is free to be turned by the ox-bow 24 and the pin 25 into the proper "on time" position. Of course, the dimensions of the re-setting elements, described hereinbefore, are such that the release of pawls 14 and 19 from ratchet wheel 4 occurs before the ox-bow 24 encounters re-setting pin 25. As soon as the impulse imparted to re-setting magnet 21 ceases, spring 26 pulls re-setting arm 22 back to the left to the position shown in Fig. 1 and the remaining elements also return to the position shown in that figure.

In order that the re-setting operation be not interfered with in case during the re-setting operation an ordinary operating impulse should be imparted to magnet 5, feeding arm 7 is locked during the re-setting operation by the following expedient. As shown in Figs. 1 and 3, the outer end of holding arm 18 is provided

with a detent 37 turned at right angles to the plane of arm 18. This detent is located in such a position with respect to a nose 17 provided at the outer end of feeding arm 7 that in normal position of arm 18 feeding arm 7 can freely move to the right in case an impulse is received at magnet 5. Thereby nose 17 passes above detent 37 and blocks upward movement of arm 18, thus locking the step wheel 4 against forward, as well as retrograde movement. If, however, the re-setting operation is in progress during which arm 18 is lifted into the position shown in Fig. 4, detent 37 has risen into alignment with nose 17 so that if now an ordinary operating impulse should be received at magnet 5 which would tend to throw the upper end of arm 7 to the right, detent 37 prevents this and thus the ordinary operating impulse remains ineffective insofar as the feeding motion of ratchet wheel 4 and the clock movement are concerned. As soon as the re-setting operation is completed, the detent drops back to the normal position shown in Fig. 1 so that feeding lever 7 is again free to operate in accordance with the operating impulses received at magnet 5.

It will be noted from Fig. 4 that there exists a time during which at the withdrawal of ox-bow 24 from pin 25 (after the re-setting has been completed) neither feeding pawl 14 nor retaining pawl 19 is in engagement with the ratchet teeth of wheel 4. In order to prevent an accidental turning of this wheel during this uncontrolled period by any cause, such as for instance the weight of the hands or other reasons, and avoid thus a disturbance of the synchronized condition of the clock, the following means are provided which are illustrated in Fig. 5. This figure only shows the central portion of the clock movement and it is assumed that the ratchet wheel 4 is located above the plane of the drawing Fig. 5. To the arbor 3, on which wheel 4 is fixed, is also fixed a holding disk 41 which is provided with a notch 42. On the clock frame 1 is pivoted at 46 a toggle lever 45 which is controlled by a toggle spring 47 fixed to frame 1 at 47a. The other end of spring 47 is attached to a pin 48 provided at the free end of lever 45. Normally, spring 47 holds lever 45 against a stop 49, but this lever, due to the toggle joint arrangement, can be swung to the right so that the pin 48 will be thrown against the periphery of disk 41. The free end of lever 45 and notch 42 of disk 41 are set in such relation that when pin 48 engages notch 42, the ratchet wheel 4 is in the synchronized position, for instance on the hour as assumed in the present example. To re-setting arm 22 is attached a toggle operating arm 43 which is provided at its end with a wide recess 44 within which pin 48 is located. Ordinarily, that is to say, when re-setting arm 22 is in the position shown in Fig. 1, recess 44 has moved the toggle joint into the position as shown in Fig. 5. As soon as re-setting arm 22 is energized by its re-setting magnet 21 and moves to the right in Figs. 1 and 5, arm 43 also moves to the right and thereby throws the toggle joint with its pin 48 against the periphery of disk 41. As soon as ox-bow 24 has completed the re-setting by moving pin 25 in Fig. 1 into the position shown, disk 41 has turned with ratchet wheel 4 into such a position that its notch 42 registers with the pin 48 so that the latter drops into the notch. In that position of the elements, the left-hand wall of recess 44 is nearer pin 48 than the right-hand

wall. Thus when after the completion of the re-setting operation spring 26 pulls re-setting arm 22 towards the left in Figs. 1 and 5, pin 48 is not yet pulled out of notch 42 by the right-hand wall of recess 44 until re-setting arm 22 has moved quite a distance towards its normal position during which the feeding pawl 14 and the holding pawl 19 have dropped back onto the teeth of ratchet wheel 4, when pin 48 is withdrawn from notch 42 and the toggle joint snaps back into the position shown in Fig. 5. Thus during the critical period, namely, while neither feeding pawl 14 nor holding pawl 19 are in engagement with the ratchet wheel and ox-bow 24 has been withdrawn from pin 25, the ratchet wheel is held by pin 48 in the proper set position until the re-setting mechanism has been restored entirely to its normal position.

In case at the arrival of a re-setting impulse at the hour, the clock should be exactly on time, it would be unnecessary to operate the entire resetting mechanism. Therefore, in order to prevent such an operation and to thereby save wear and tear on this mechanism, the following means are provided. On ox-bow 24 is mounted a pin 40 which extends toward ratchet wheel 4, and on ratchet wheel 4 is mounted a spring 39 in such a position that its free end is exactly in line with pin 40 when the clock is on time. Thus if now a re-setting impulse is imparted to electromagnet 21 and the latter attempts to attract its armature, pin 40 impinges against the end of spring 39 and thus prevents ox-bow 24 from moving toward pin 25 and thus locks the entire re-setting mechanism.

I claim:

1. In a secondary clock movement having a toothed step wheel connected to a hand arbor, an oscillating feed member bearing a pivoted feed pawl engageable with the teeth of said step wheel, a pivoted stop positioned over said feed pawl at the forward limit of its movement to

block pivotal movement of said feed pawl outward from said step wheel, resetting means for said hand arbor, and means operated by said resetting means for swinging said stop away from said feed pawl and tilting the latter out of engagement with said step wheel.

2. In a secondary clock movement having a step wheel connected to a hand arbor, a feed member having an oscillating movement to feed said step wheel, means for resetting said hand arbor, and means operable by said resetting means to block the oscillation of said feed member.

3. In a secondary clock movement, a hand arbor unit, feed means to move said hand arbor unit progressively, resetting means engageable with said hand arbor unit to set the same to a definite position, means for moving said resetting means to setting position and back to position of rest, and holding means engageable with said hand arbor unit when it is set to said definite position by said resetting means, to hold said hand arbor unit while said resetting means returns to position of rest.

4. In a secondary clock movement, a hand arbor unit comprising a step wheel, a feed member engageable with said step wheel to move said hand arbor unit progressively, a holding pawl coacting with said step wheel to prevent retrograde movement thereof, resetting means engageable with said hand arbor unit to reset the same to a definite position, means for moving said resetting means to resetting position and back to position of rest, means operated by said resetting means to disengage said holding pawl from said step wheel during the resetting operation, and a detent controlled by said resetting means to lock said hand arbor unit in said definite position during the return of said resetting means to position of rest.

LUCIEN B. STONE.
